US00D926900S

(12) **United States Design Patent** (10) Patent No.: **US D926,900 S**
Nicolette et al. (45) Date of Patent: **** Aug. 3, 2021**

(54)	GOLF CLUB HEAD	D261,167	S	10/1981	Swanson
(71)	Applicant: PARSONS XTREME GOLF, LLC , Scottsdale, AZ (US)	D294,617	S	* 3/1988	Perkins .....
		4,754,977	A	* 7/1988	Sahm A63B 53/047 473/337
(72)	Inventors: Michael R. Nicolette , Scottsdale, AZ (US); Bradley D. Schweigert , Cave Creek, AZ (US)	4,824,116	A	4/1989	Nagamoto
		4,988,104	A	1/1991	Shiotani
(73)	Assignee: PARSONS XTREME GOLF, LLC , Scottsdale, AZ (US)	5,158,296	A	* 10/1992	Lee A63B 53/047 473/327
(***)	Term: 15 Years	5,176,384	A	1/1993	Sata
(21)	Appl. No.: 29/711,139	5,213,328	A	5/1993	Long
(22)	Filed: Oct. 29, 2019	D336,672	S	6/1993	Gorman
